Henry G. Reed, of Taunton, Mass.
Letters Patent No. 1343, Dated Nov. 13th 1860.

The schedule referred to in these ^{numbers} Letters Patent and making part of the same.

To all Persons to whom these Presents shall come:

Be it known that I, Henry G. Reed, of Taunton, in the County of Bristol and State of Massachusetts, have invented or produced a new ornamental design for a Tea Service, and I do hereby declare the same to be fully represented in the accompanying drawing, which exhibits a side elevation of it, and shows it as provided with an ornamental spout and handle.

The design covers the stand, body and neck of the vase,

Res. 1343

also the handle, cover and spout, and may be used in a tea service as circumstances may require. On the body of the vase there is a shield with a border in bas relief - the whole being based upon an engine chased and banded ground.

I claim the design as above explained and as represented in the accompanying drawing.
